[57] CLAIM

The ornamental design for a golf club head, as shown.

DESCRIPTION

FIG. 1 is a bottom view of the golf club head;
FIG. 2 is a perspective view looking generally at the striking face and the bottom of the golf club head;
FIG. 3 is an elevational view looking at the toe of the golf club head;
FIG. 4 is an elevational view looking at the hosel end of the golf club head;
FIG. 5 is an elevational view looking at the trailing side of the golf club head;
FIG. 6 is a plan view of the golf club head;
FIG. 7 is an elevational view looking at the striking face of the golf club head;
FIG. 8 is an elevational view of a modified golf club head looking at the striking face thereof;
FIG. 9 is a bottom view of the golf club head shown in FIG. 8; and
FIG. 10 is an elevational view of the golf club head of FIG. 8 looking at the hosel end of the golf club head.
